Primary Examiner — Paula Allen Greene

(74) Attorney, Agent, or Firm — Robert L. Stearns;
 Dickinson Wright PLLC(57) **CLAIM**

The ornamental design for an earphone, as shown and described.

DESCRIPTION

FIG. 1 is a top, front, right side perspective view of an earphone showing my new design, the opposite mirror image earphone is evident from the earphone shown;

FIG. 2 is a front elevation view thereof;

FIG. 3 is a rear side elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is an enlarged view of a part of FIG. 4; and,

FIG. 9 is an enlarged view of a part of FIG. 7.

The dot dash broken lines encircling portions of FIGS. 4 and 7 and illustrated in the enlarged views of FIGS. 8 and 9 form no part of the claimed design.

1 Claim, 9 Drawing Sheets(56)
